UNITED STATES PATENT OFFICE.

JULIUS M. BLANCHARD, OF OAK PARK, ILLINOIS, ASSIGNOR OF ONE-HALF TO J. W. MABBS, OF CHICAGO, ILLINOIS.

SHIPPING BOX.

Application filed March 11, 1927. Serial No. 174,435.

The invention relates to shipping boxes and more particularly to those boxes which are formed of sheet material such as fibre board.

5 Hertofore, fibre board shipping boxes have been impractical for use in shipping heavy articles because they would break or crack due to the weight and pressure of the articles.

10 The primary object of the present invention is to provide a fibre board shipping box which will withstand severe handling and will not break or crack when used for shipping heavy articles. The top, bottom 15 and sides of this box are constructed so that each consists of an inner and outer fibre board wall and separately formed hollow cylindrical reinforcing members which are disposed between and are secured to the 20 walls.

Another object of the invention is to provide a fibre board shipping box which may be readily hermetically sealed.

25 A further object of the invention is to provide a shipping box which is of new and improved construction and can be produced at a low cost.

Other objects will be apparent from a consideration of the following detail description.

30 The invention consists in the several novel features hereinafter set forth and more particularly defined by claims at the conclusion hereof.

35 In the drawings: Fig. 1 is a perspective of a box embodying the invention, portions being broken away for the purpose of illustration. Fig. 2 is a vertical section of the box. Fig. 3 is a section on line 3—3 of Fig. 2. Fig. 4 is a perspective of one of the reinforcing members. Fig. 5 is a section through one of the handles for the box. Figs. 6 and 7 are detail perspectives showing modified forms of reinforcing members.

45 The invention is exemplified in a rectangular shipping box comprising sides 10, a top 11 and a bottom 12. Each side consists of an outer wall 13 and an inner wall 14 which is spaced from the outer wall as 50 hereinafter described. The outer walls 13 are formed from a strip of fibre board which is creased as at 15 to form the corners of the box and has its end margins secured together by a strip 16 of adhesive tape.

55 The inner walls 14 are also formed of fibre

board and each is separate from the others and provided with a flap 17 at its top margin, a flap 18 at its bottom margin, and flaps 19, 20 at its side margins. These flaps extend outwardly and have their outer 60 edges glued to walls 13. They serve as spacing means for inner walls 14, and form with the latter and the outer wall 13, hollow compartments 10^a. Flaps 17 and 18 are flush with the top and bottom edges of outer 65 walls 13 respectively. Flaps 19 are disposed inwardly of the side edges of the outer walls so as to expose marginal portions 21 on the inner faces of said outer walls. Each of the flaps 20 abuts against 70 and is glued to the marginal portion 21 on the outer wall 13 of the side which is contiguous to it. Each of the flaps 19 abuts against and is glued to one of the 75 side margins of inner wall 14 of the side which is contiguous to it. By gluing flaps 19 and flaps 20 as set forth the corners of the box are strengthened so that they will withstand severe handling without breaking and will prevent the sides 10 from 80 collapsing.

Top 11 consists of an outer wall 22 and an inner wall 23 both of which are formed of fibre board. The inner wall 23 is provided with upwardly extending marginal 85 flaps 24 which have their upper edges glued to wall 22. These flaps are spaced inwardly from the edges of wall 22 and are adapted to engage the upper margins of walls 14 when the top is in its operative 90 position. Flaps 24 serve as spacing means for wall 23 and form with the latter and wall 22 a hollow compartment 11^a. The exposed margins of wall 22 rest upon flaps 17 when the top is in its operative position. 95 To secure the top in this position flaps 24 are glued to the upper margins of walls 14 and flaps 17 are glued to the margins of wall 22. To additionally secure top 11 in its operative position, a pair of extensions 100 25 are provided. These extensions are formed integrally with the outer walls 13 of two of the sides and are adapted to be folded over outer wall 22. Extensions 25 may be secured together by any suitable 105 means.

Bottom 12 is formed similarly to top 11 and consists of an outer fibre board wall 26 and an inner fibre board wall 27 which is provided with downwardly extending flaps 110

28. The latter form with walls 26 and 27 a hollow compartment 12^a. Flaps 28 are glued to the lower margins of walls 14 and flaps 18 are glued to the exposed margins of wall 28 so as to secure the bottom in place. The bottom is additionally secured in place by a pair of extensions 29 which are similar to extensions 25. These extensions are folded over outer wall 26 and are secured together by any suitable means. Extensions 25 and 29 serve, respectively to strengthen the top and bottom of the box. A characteristic of the specific flap construction set forth is that the flaps, when glued respectively to the surfaces adjacent them form a hermetical seal for the box.

In Figs. 1 to 5 of the drawings, compartments 10^a are shown filled with separately formed hollow reinforcing members 30. These members extend transversely to the compartments in which they are disposed and extend completely throughout the latter's area. Members 30 have their sides glued together and their ends glued to walls 13 and 14 respectively. This makes sides 10 substantially rigid and reinforces them so that they are capable of withstanding great weight and pressure. Hollow compartments 11^a and 12^a are filled respectively with reinforcing members 31 and 32 which are similar to members 30. Members 31 have their sides glued together and their ends glued respectively to walls 22 and 23. Members 32 have their sides glued together also and their ends glued respectively to walls 26 and 27.

Fig. 6 illustrates reinforcing members 33 which are of a slightly modified form. These members comprise hollow cylinders which extend parallel to the compartments. The sides of members 33 are glued to each other and to the inner and outer walls of the compartment in which they are disposed.

Fig. 7 illustrates reinforcing members 34 of another form. These members are semi-cylindrical and extend similarly to members 33. The edges of members 34 are glued to the outer wall of the compartment in which they are disposed and the sides are glued together and to the inner wall.

To facilitate handling, the box is provided with handles. These handles are disposed at opposite sides of the box and comprise members 35 which extend through openings 36 in walls 13. These members are disposed completely within compartments 10^a and are surrounded by reinforcing members 30. They have finger openings 37 at one side thereof and are provided with flaps 38 which extend outwardly and are glued to the outer face of walls 13 so as to secure the members in place.

The invention exemplifies a fibre board shipping box which may be hermetically sealed and is so constructed that it will with-

stand severe handling and will not break or crack when used for shipping heavy articles.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. A shipping box comprising a top, bottom, and sides, each of said sides consisting of an inner and outer wall of sheet material, and separately formed reinforcing members between the walls, said members being closely arranged and substantially filling the space between the walls.

2. A shipping box comprising a top, bottom, and sides, each of said sides consisting of an inner and outer wall of sheet material, and separately formed cylindrical reinforcing members between the walls, said members being closely arranged and substantially filling the space between the walls.

3. A shipping box comprising a top, bottom, and sides, each of which consists of an inner and outer wall of sheet material, and separately formed reinforcing members between the walls, said members being closely arranged and substantially filling the space between the walls.

4. A shipping box comprising a top, bottom, and sides, each of which consists of an inner and outer wall of fibre board, and separately formed cylindrical reinforcing members between and secured to the walls, said members being closely arranged and substantially filling the space between the walls.

5. A shipping box comprising a top, bottom, and sides, each of said sides consisting of an inner and outer wall of sheet material, and hollow cylindrical members between and extending transversely to the walls, said members being held in abutting relation and operating to reinforce the walls of said sides.

6. A shipping box comprising a top, bottom, and sides, each of which consists of an inner and outer wall of sheet material, and cylindrical reinforcing members between and extending transversely to the walls, said members having their sides rigidly connected together and their ends secured respectively to said inner and outer walls.

7. A shipping box comprising a top, bottom, and sides, each of which consists of an inner and outer wall of sheet material, said inner wall having outwardly extending marginal flaps secured to the marginal parts of the outer wall and operative to space the walls apart, and reinforcing members substantially filling the space between the walls of said top, bottom and sides.

8. A shipping box comprising a top, bot-

tom, and sides, the bottom consisting of an inner and outer wall of sheet material, said inner wall being spaced from the outer wall and forming therewith a chamber, and separately formed reinforcing members, said members being arranged in close proximity to each other and substantially filling said chamber.

9. A shipping box comprising a top, bottom, and sides, the bottom consisting of an inner and outer wall of sheet material, said inner wall being spaced from the outer wall and forming therewith a chamber, and hollow transversely extending cylindrical reinforcing members filling said chamber.

10. A box for shipping heavy articles, comprising a top member, a bottom member, and side members, one of said members con-

sisting of an inner and outer wall of sheet material and having separately formed reinforcing members disposed between the walls, said members being arranged in close proximity to each other and substantially filling the space between said walls.

11. A box for shipping heavy articles, comprising a top member, a bottom member and side members, one of said members consisting of an inner and outer wall of sheet material and having hollow substantially cylindrical members disposed between the walls, said members being arranged in close proximity to each other and substantially filling the space between said walls.

Signed at Chicago, Illinois, this 9th day of March, 1927.

JULIUS M. BLANCHARD.
